2 SHEETS—SHEET 2.

UNITED STATES PATENT OFFICE.

FRANK T. WIECHERT, OF LAKWOOD, OHIO, ASSIGNOR OF ONE-HALF TO GEORGE W. WISE, OF CLEVELAND, OHIO.

SODA-FOUNTAIN.

1,394,130.

Specification of Letters Patent. Patented Oct. 18, 1921.

Application filed September 22, 1920. Serial No. 411,894.

To all whom it may concern:

Be it known that I, FRANK T. WIECHERT, a citizen of the United States, residing at Lakewood, in the county of Cuyahoga and 5 State of Ohio, have invented certain new and useful Improvements in Soda-Fountains, of which the following is a specification.

My invention relates to the construction of soda-fountains, and it has particular reference to a sheet-metal body structure adapted to the application of the outer facing panels and service counter of wood or marble of a more or less ornamental nature as desired.

15 The primary object of the present invention is the provision of a sheet-metal body structure that is strong, durable, and economical to manufacture, and that is convenient and efficient. Coincident to the general 20 object, the invention provides a novel construction and arrangement of the cooling compartment and its accessories. It further provides novel convenient means for extracting ice-cream containers from their receptacles in the cooling compartment.

With these and other apparent objects in view, the invention consists in the construction, combination and arrangement of elements as hereinafter fully described and 30 pointed out definitely in the appended claims, reference being had to the accompanying drawings which are made part of the specification, similar reference characters being employed to designate corresponding parts.

35 In the said drawings Figure 1 is a rear elevation of the improved fountain structure. Fig. 2 is a section on line 2—2 of Fig. 1. Fig. 3 is a section on line 3—3, Fig. 1. Fig. 4 is a vertical median section through one 40 of the ice-cream-can receptacles, and Fig. 5 is a similar section taken at right angles to that of Fig. 4. Figs. 6, 7, 8 and 9 are fragmentary views illustrative of a novel hinged cover construction embodied in the invention.

45 The improved structure comprises a front wall 1, end walls 2, and a bottom 3 of sheet-metal riveted together. The front and end members are vertical and form a foundation for the facing members 4 and serving 50 counter 5.

The cooling compartment comprises inner

and outer rectangular walls or casings spaced from each other for the reception of suitable insulating material 6 commonly used in apparatus of this character. The said outer 55 rectangular casing comprises lateral or side walls 7, and corresponding end walls, said walls of the outer casing being provided with inwardly extending flanges 7^a, at the bottom for receiving and carrying a bottom wall 8, 60 and being provided along their upper marginal edges with inwardly extending flanges 7^b, said inwardly extending flanges 7^b, at the top, bridging over the space between the inner and outer casings, the inner casing including lateral walls 9, and corresponding 65 end walls, and a bottom wall 10, said lateral and end walls having bottom flanges 9^a which receive and carry the bottom 10, and having upper flanges 9^b for attachment to the 70 flanges 7^b.

The rectangular box-like cooling compartment, thus formed, is set into the body structure on a laterally inclined plane relatively to said body structure, as best shown in Figs. 75 2 and 3, the inner lower corner of said cooling compartment being firmly attached to the wall 1 at a distance above the bottom 3, as indicated at 1^a, and the outer lower corner being in like manner attached to the bottom 80 wall 3, as indicated at 3^a. Several advantageous features are attained by the peculiar position of the cooling compartment. Prominent among these advantages, is the convenience afforded the attendant by the receding 85 of the cooling structure from the top to the bottom, which allows foot clearance, or a natural position, with the body of the attendant close up to his work. It also provides a desirable space 1^b back of the compartment, to accommodate the syrup jars 11. It further facilitates the icing of the apparatus, by providing easy or convenient access 90 to the interior of the compartment for charging it with ice, and allowing a larger space, 95 more effectively disposed, than in the structures heretofore in common use.

An angle iron 12 extends longitudinally the entire length of the top of the cooling compartment. The portion 13 of the top, 100 forward of said member 12 is in a horizontal plane, while the portion 14 back of said

member 12 is inclined, as shown. An opening 13^a is provided in the top 13, said opening being provided with a removable cover 15. Sub-compartments are provided for ice-5 cream containers, said sub-compartments being of novel efficient construction, as follows: A plate 16, having under-turned flanges 16^a provides an auxiliary bottom and a support for perforated jackets 17, said 10 jackets being attached to said plate 16 and extending upward therefrom form receptacles for the ice-cream containers. The flanges 16^a resting on the bottom 10, elevate the member 16, thereby allowing the brine 15 or cooling medium to flow between said plate 16 and the bottom 10, under the sub-compartments or receptacles 17. Collars 18 fit snugly around the jackets 17 adjacent to the tops thereof, above the perforations 17^a, said 20 collars being supported by skirts 19 which are attached along their upper marginal edges to the inclined top element 14, around openings 14^a provided therein, the said openings being directly over the tops of the 25 jackets 17, and provided with covers 20. This novel detail of construction provides for the exclusion of outside air from the ice compartment when the covers 20 are open, or when ice-cream containers are being inserted 30 in, or extracted from the jackets 17 through the openings 14^a. Stabilizing, spacing elements 17^b are attached to the jackets 17 and bear on the wall of the cooling compartment. Means are provided for facilitating the 35 withdrawal of the ice-cream containers from the receptacles 17, said means comprising a bar 21 provided with a handle 21^a, adapted to slide vertically in bearings 22 attached to the interior of the jackets in vertical alignment. The bar 21 is provided with an in-turned element or rest 21^b at the lower terminal thereof. Said rest 21^b extends under the bottom of the ice-cream container when it is inserted in the jacket 17, as shown in 40 Fig. 4, the ice-cream container being indicated by broken lines 23. It will readily be seen that the container can be elevated, by the pulling upward of the bar 21, a sufficient distance to allow it to be easily or freely 45 grasped by the hands of the attendant.

The cooling compartment is subdivided by a partition 24, shown in Fig. 2, and by broken line in Fig. 1, thus providing a convenient receptacle 25 for bottled goods. 50 This division feature is not broadly new, but the peculiar construction, or inclined structure makes the bottle compartment more convenient. A cold air radiator 26 is provided in the compartment 25, and a pipe 27 is connected with the icing compartment, and passes through sub-compartment 25, for carrying off the waste brine which accumulates in said icing compartment.

The member 13^b extends upward, on a 60 slant, from the horizontal plane top 13 and

forms a support for the syrup jars, as best shown in Fig. 3, the said jars depending in the space 1^b between the cooling compartment and the front wall 1 of the structure. A longitudinal stiffening brace member 28 70 is firmly attached to the walls 1 and 7. Feet 29 attached to the bottom 3 elevate the structure from the floor, thereby allowing an air space 30 under the structure. The inclined position of the cooling compartment also 75 provides an air space 31 which is a desirable feature.

Novel hinge connections are provided for the covers 20, whereby said covers may be easily and quickly detached, and also perform their required functions effectively when connected with the structure. Accordingly, open hinge butts 32 are attached to the cover members 20. The butts 32 are adapted to extend beneath staples 33 which are attached to the top member 14. A depression 32^a in the member 32 provides a bearing for the staple 33. An extension 32^b forms a stop which limits the upward movement of the cover, as shown in Fig. 9. It is 80 obvious that when the cover is in the position shown in Fig. 9, it can be readily freed from the hinge member 33, and when connected, as shown, the hinge will function 85 properly.

From the foregoing description, taken in connection with the accompanying drawings, the operation and advantages of my invention will be readily understood.

What I claim and desire to secure by Letters Patent is.

1. In a soda fountain, a vertical sheet-metal supporting structure including front, bottom, and end walls, means for supporting the bottom of said structure, a rectangular 105 cooling compartment structure set into said supporting structure and attached to the walls thereof in a vertically inclined position, the lower inner longitudinal corner of said cooling compartment being attached to the front wall of said supporting structure at a distance above the bottom of said supporting structure, and the lower outer longitudinal corner being attached to the bottom wall of the supporting structure, said 110 cooling compartment provided with a top member the front portion of which is in a horizontal plane and the rear portion inclining therefrom, openings in the horizontal plane portion and openings in the inclined portion of the top, and closure members for 115 said openings.

2. In a soda fountain, a cooling compartment vertically inclined outward from the bottom, ice-cream receptacles arranged in 120 said compartment adjacent to the outer wall thereof and attached to an auxiliary bottom provided in said compartment, said receptacles being perforated, a top for the compartment, said top being provided with 125 130

openings which register with the tops of the receptacles, covers for said openings, connecting means between the top of the compartment and the receptacles for excluding outside air from the compartment around the receptacles when the covers are open, and vertically slidable bars mounted in bearings inside the receptacles, said bars having projections thereon which engage the ice-cream containers, whereby said containers may be elevated in the receptacles.

In testimony whereof I affix my signature.

FRANK T. WIECHERT.
